(57) **CLAIM**

The ornamental design for a controller holder as shown and described.

DESCRIPTION

FIG. 1 is a top-front-left perspective view of a controller holder according to the claimed design.

FIG. 2 is a bottom-front-right perspective view of the controller holder.

FIG. 3 is a right side view of the controller holder.

FIG. 4 is a left side view of the controller holder.

FIG. 5 is a front view of the controller holder.

FIG. 6 is a rear view of the controller holder.

FIG. 7 is a top view of the controller holder.

FIG. 8 is a bottom view of the controller holder; and,

FIG. 9 is a front perspective view of the controller holder, with a controller shown in environment.

The broken lines in the drawings illustrate environmental subject matter that forms no part of the claimed design.
